CLAIM

I claim the ornamental design for a bird cage, as shown and described.

DESCRIPTION

FIG. 1 is a perspective view of a bird cage showing my new design.

FIG. 2 is a front elevational view of the bird cage of FIG. 1. FIG. 3 is a rear elevational view of the bird cage of FIG. 1. FIG. 4 is a right side elevational view of the bird cage of FIG. 1.

FIG. 5 is a left side elevational view of the bird cage of FIG. 1.

FIG. 6 is a top plan view of the bird cage of FIG. 1; and, FIG. 7 is a bottom plan view of the bird cage of FIG. 1. The broken lines in the figures depict portions of the bird cage that form no part of the claimed design.
